UNITED STATES PATENT OFFICE

MAURICE M. SAMUELS, OF NEW YORK, AND FRANK J. DOUGLAS, OF LONG ISLAND CITY, NEW YORK, ASSIGNORS TO WESTINGHOUSE ELECTRIC AND MANUFACTURING COMPANY, A CORPORATION OF PENNSYLVANIA

INCLOSED SWITCHING DEVICE

Application filed September 20, 1930. Serial No. 483,254.

Our invention relates to a switching structure of the type in which metallic cubicles are used to enclose a switching apparatus, with means for operating such apparatus 5 from the exterior of the cubicle.

An object of the invention is to provide a structure which shall be flexible in design, so that it can be used for a large number of different types of circuits.

10 Another object of the invention is to provide a switch structure, which shall be compact in arrangement and economical of space.

A further object of the invention is to provide separate cubicles for the outgoing 15 feeder and the circuit breaker, and to separate the two incoming busses.

A further object of the invention is to provide a disconnect switch so mounted that all three phases may be operated together 20 from the exterior of the cubicle.

A further object is to provide a mimic bus on the face of the cubicle to indicate the positions of the disconnect switches at all times.

25 These and further objects of the invention will be made apparent from the further description of the invention, a particular embodiment of which is illustrated in the drawings in which,

30 Figure 1 is a sectional view through two cubicles comprising a section of the switchboard, showing the interiors of the cubicles,

Fig. 2 is a front view of the structure 35 showing two adjacent cubicles, one of which has its front and its circuit-breaker operating means removed, to show the interior structure,

Fig. 3 is a sectional view of the rear cubicle, taken on the line III-III of Fig. 1 40 with its interior shown in elevation.

Figs. 4 to 8 inclusive are a series of diagrammatic sketches indicating the different types of connections which may be employed,

45 Fig. 9 is a sectional view through the front cubicle, showing the construction of the three-phase disconnect switch and its operating means,

Fig. 10 is a sectional view through Fig. 9 50 on the line X-X,

Fig. 11 is an enlarged front view of a portion of the front panel, illustrating the mimic bus,

Fig. 12 is a sectional view through Fig. 11 on the line XII-XII.

The switch structure is built up by placing together a plurality of cubicles, using as many sections as is desired. Each section is composed of a front cubicle 1 and a rear cubicle 3 secured together in back-to-back relation.

The front cubicle has a back wall 5, side walls 7 and top 9, with a front 11 hinged to the side walls at 13. The rear cubicle 3 is similarly built up with the door opening 65 in the rear. These cubicles are constructed of sheet metal by welding the over-lapped edges together, as at 15.

A circuit breaker 17 is mounted in the front cubicle 1 by suitable means (not 70 shown). Mounted upon the breaker, is an operating mechanism indicated at 19 and having a handle 21, at the front of the cubicle. A rectangular portion 23 is cut from the front door 11 of the cubicle so that the 75 door may open around the circuit-breaker handle 21. On the rear wall 5 of the front cubicle 1 are mounted two disconnect switches 25 and 27, of a type to be more fully described later. A third disconnect 80 switch 26 is mounted in the rear cubicle in back-to-back relation to the upper disconnect switch 27 in the front cubicle. A feeder 29 enters the rear cubicle 3 from the bottom and is connected, through suitable 85 current transformers 31, potential transformers 33 and busses 35, 37, and 39 to the disconnect switches and the circuit breaker. In the top of the front cubicle is mounted a three-phase bus 41 and in the rear cubicle, 90 a bus 43 is mounted. While the connections shown in Fig. 1 are to be described for only a single phase, it should be understood that each phase is similarly connected.

95 This switch structure is particularly adapted to be used for a plurality of different connections. These are illustrated diagrammatically in Figs. 4 to 8, inclusive. In Fig. 4, the bus 41 is connected to the 100

outgoing feeder 29, through a single disconnect switch 27 and the circuit breaker 17. For this simple connection, only the single front cubicle 1 would be used with a connection 45 from the bus 41 to the upper disconnect switch 27, through the connecting bus 37 to the circuit breaker 17, the other terminal of which would go directly to the feeder 29.

10 If a connection, as shown in Fig. 5, is desired, the connection will be from the bus 41 in the front cubicle, through the upper disconnect switch 27, to one terminal of the circuit breaker 17, and from the other terminal of the circuit breaker to the lower disconnect switch 25, the other side of which is connected to the outgoing feeder 29 through conducting bolt 47 and transformer 31.

20 Fig. 6. illustrates a connection in which a disconnect switch is provided on each side of the circuit breaker, with an additional disconnect switch to make a connection around the breaker. With this connection, 25 the bus 41 is connected to the upper terminal of the upper disconnect switch 27 in the front cubicle, which is electrically connected, by a through bolt 49, to the upper terminal of the disconnect switch 26 in the 30 rear cubicle 3. The bolt 51 through the lower ends of the disconnect switches 26 and 27 is then made of insulating material. The busses 37 and 39 then connect, through the circuit breaker 17, to the lower end of 35 the lower disconnect switch 25. The upper end of this disconnect switch is then connected to the bus 35 in the rear cubicle by means of conducting bolt 47. Bus 35 is connected, at its upper end, to the lower end of 40 the rear disconnect switch 26 and, at its lower end, to the outgoing feeder 29.

In Fig. 7, a connection is illustrated in which the feeder 29 may be connected either to a main bus 41 through the circuit breaker 45 17, with a disconnect switch on each side of the breaker, or to a transfer bus 43 through a single disconnect switch. With this connection, both of the through bolts 49 and 51 between the upper disconnect 50 switches 26 and 27 are of insulating material, so that one circuit is provided from the main bus 41 in the front cubicle, through the upper disconnect switch 27, circuit breaker 17, and lower disconnect switch 55 25, to the feeder 29. Another circuit leads from the transfer bus 43 in the rear cubicle, through the rear disconnect switch 26 and rear bus 35, to the outgoing feeder 29.

In Fig. 8, the connection is of the type 60 in which the feeder may be connected through the circuit breaker, selectively, to either of two main busses. With this connection, the upper through bolt 49 is of insulating material, and the lower through 65 bolt 51 is of conducting material for con-

nnecting the upper disconnect switches 26 and 27. The short bus 35 between the upper disconnect switch 26 and bolt 47 in the rear cubicle is not used. In this way, the bus in either cubicle may be connected, 70 through a disconnect switch, to one terminal of the circuit breaker, with its other terminal connected to the outgoing feeder.

In order to provide ease of operation, the disconnect switches are each arranged so 75 that all three phases may be opened or closed together. The structure of the disconnect switches is illustrated in Figs. 9 and 10. The switch blades 53 are mounted upon the cubicle by insulators of post or pillar type and are pivoted on clips 55 mounted on insulators 57 to engage a spring clip 59 on the opposite insulator 60. The three switch blades 53 are connected together through connecting insulators 61. The 80 blades 53 are connected to the insulators 61 by means of bolts 63, which engage studs 65 cemented in the ends of the insulators 61. The bolts 63 are so arranged that the knife 85 blades 53 may turn about the insulators 61. This gives a rigid connection between the three knife blades so that they may be operated in unison.

Around the center of each connecting insulator 61, is secured a strap 67 for connecting the insulator to one end of a lever 69 which is connected, at its other end 71, to a crank 73 to be secured on a shaft 75 extending between the supporting insulators 57 and 60. It is thus seen that rotation of the 90 shaft 75 so operates the crank 73 that the switch may be opened or closed by a rotating movement of the shaft of 90°. The shaft 75 is supported by lugs 77 welded to the wall of the cubicle. One end of the 95 shaft 79 has a bevel gear 81 mounted thereon, which is supported from the cubicle by a rectangular piece of sheet metal 83 welded to the cubicle. A second bevel gear 85 engages the first gear 83 and has a shaft 87 extending therefrom to the front 11 of the cubicle. The shaft 87 has a square end 89 to be engaged by a key 91, which is inserted through a hole 93 in the front of the cubicle. 100

From Fig. 2, it is seen that the shafts 87 from the three disconnect switches 25, 26 and 27 are brought out along the edges of the front panel 11. A mimic bus is arranged on the front 11 to represent the interior bus structure, with the main busses 95 and 97 across the top of the panel and the busses 99 and 101 connecting to the feeder 103 extending down the edges of the panel. This 105 leaves the center of the panel clear for the placing of meters 105 or relays 107.

Referring to Figs. 11 and 12, the positions of the disconnect switches are indicated by short sections 109 of the mimic bus, which are rotated when the key 91 is rotated in the hole 93 to operate the disconnect. The short 110

section of bus 109 is supported by sleeve 111 through the panel 11 and has a collar 113 behind the panel. The panel is provided with two slots 115 and 117 at 90° to each other. The key 91 has a projection 119 which fits in the slots 115 and 117, so that the key cannot be removed until the disconnect switch is in either fully-opened or fully-closed position. This projection 119 also 10 engages a slot 121 in the rear collar 113 so as to turn the indicating section 109 of the mimic bus.

Thus, it is seen that a switch structure has been provided which is fully enclosed but 15 yet easily operated from the exterior and which is very compact in design and most conveniently operated.

While a particular embodiment of the invention has been described, it should be understood that various modifications may be 20 made without departing from the scope and spirit of the invention as defined in the following claims.

We claim as our invention:

- 25 1. In electric-switch gear, a metal cubicle, a disconnect switch mounted on one wall thereof by means of insulating pillars, a second metal cubicle, a second switch similarly mounted in the second cubicle, said two cubicles being secured, together with said 30 switches, in back-to-back relation, and an electrical connection between said switches through said insulating pillars.
2. In electric switch-gear, a metal cubicle, a disconnect switch mounted on one wall thereof by means of insulating pillars, a second metal cubicle, a second switch similarly mounted in the second cubicle, said two cubicles being secured, together with said 35 switches, in back-to-back relation, an electrical connection between one end of said switches through said insulating pillars, and other of said insulating pillars keeping the other ends of said switches insulated from each other.
3. In electric switch-gear, a metal cubicle, a disconnect switch mounted on one wall thereof by means of insulating pillars, a second switch similarly mounted in another 40 cubicle, said two cubicles being secured, together with said switches, in back-to-back relation, and an electrical connection between said switches through said insulating pillars, and means for operating both of said 45 switches from the front of one of said cubicles.
4. In electric switch-gear, a metal cubicle, a disconnect switch mounted therein and operated by the rotation of a shaft extending 50 to the front of said cubicle, a key for turning said shaft, and means for preventing the removal of said key from said shaft unless the switch is in the fully-open or fully-closed position.
5. In electric switch-gear, a pair of metal

cubicles secured in back-to-back relation, a disconnect switch in each cubicle, insulating pillars for mounting both ends of said disconnect switches on the adjacent opposing walls of the cubicles, insulating pillars in 70 one cubicle being arranged in aligned relation with the respective insulating pillars of the other cubicle, said aligned insulating pillars being adapted to have a conducting bolt extend therethrough to electrically connect the adjacent ends of said switches, whereby a structure is provided which is applicable to a plurality of circuit connections by providing conducting bolts in the appropriate pairs of aligned insulating pillars.

In testimony whereof, we have hereunto subscribed our names this 14th day of August, 1930.

MAURICE M. SAMUELS.
